CLAIM

The ornamental design for a speaker housing, as shown and described.

DESCRIPTION

FIG. 1 is a perspective view of a speaker housing showing my new design;

FIG. 2 is a front elevational view thereof;

FIG. 3 is a side elevational view of one side thereof, the opposite side being a mirror image;

FIG. 4 is a rear elevational view thereof; and,

FIG. 5 is a top plan view thereof.

The broken line showing of the circular area on the front of the speaker housing is for illustrative purposes only and forms no part of the claimed design.
